UNITED STATES PATENT OFFICE.

WALTER BURNHAM, OF CHICAGO, ILLINOIS.

WATER-RAISING CONNECTION FOR STEAM-GENERATORS.

SPECIFICATION forming part of Letters Patent No. 394,822, dated December 18, 1888.

Application filed February 21, 1888. Serial No. 264,806. (No model.)

To all whom it may concern:

Be it known that I, WALTER BURNHAM, of Chicago, in the county of Cook and State of Illinois, have invented certain new and useful 5 Improvements in Water-Return Connections for Steam-Generators; and I do hereby declare that the following is a full, clear, and exact description thereof, reference being had to the accompanying drawings, and to the letters 10 of reference marked thereon, which form a part of this specification.

This invention has for its object to improve the operation of the system of pipe-connections for steam-generators invented by William Irving, of Chicago, Illinois, and described in his two applications for Letters Patent, Serial Nos. 263,224 and 263,225, filed February 7, 1888, and illustrated in its general features in Figure 1 of the accompanying drawings.

20 The improvements herein described and claimed relate, first, to provisions for preventing the breaking or separation of the body of water or liquid column in the delivery end of the return-pipe of said Irving system, and, 25 secondly, to a provision for improving the action of the low-pressure space within said return-pipe as a condensing-chamber.

The nature of my improvements will be understood from the following description of 30 the accompanying drawings.

Fig. 1 of said drawings represents the Irving system referred to in that form thereof wherein the water of condensation and entrainment is raised from a point in a steam-supply pipe below the water-level of the generator in its return to the latter. Fig. 2 shows the leg of the return-pipe having its end upturned, but terminating below the water-level in the generator. Fig. 3 shows the leg of the 40 return-pipe provided with a longer upturned end terminating in the steam-space of the boiler, the **U** thus formed extending in the water-space as an incident to the location of said **U** within the generator. Fig. 4 shows the return-pipe provided with a **U** essentially like that of Fig. 3, but outside the generator and having the open end of said pipe terminating in the steam-space of the generator. Fig. 5 shows the Irving return-pipe made straight 45 and provided with a deflecting-plate below its open and downwardly-directed end for the deflection of rising bubbles of air or gas, so as

to prevent their entering the return-pipe. Fig. 6 is a top view of the deflecting-plate obtained by horizontal section of the return-pipe in the line 6 6 of Fig. 5. The foregoing figures have reference to the improvement first above mentioned. Figs. 7 and 8 relate to the improvement in the low-pressure or condensing chamber of the Irving return-pipe, 55 Fig. 7 showing the improvement as consisting simply in an enlargement of the return-pipe at a point in the leg thereof above the valve and escape-pipe, and Fig. 8 showing one form of means by which such an enlargement of 60 the return-pipe—as a steam-space—may be varied at pleasure. Fig. 9 shows an enlargement of the return-pipe adjustable vertically upon a part or branch of said return-pipe as another form of means by which the steam-space in such enlargement may be varied at 65 pleasure.

First briefly describing the Irving system as illustrated in Fig. 1, A is a steam-generator; B, a steam-pipe leading therefrom, which 70 in this instance extends to a point below the water-level in the generator.

C is a return-pipe communicating with the steam-pipe B at a point below the water-level of the generator, thence rising to a point 75 above the generator and descending into the water-space of the generator, where it terminates in an open downwardly-directed end. Said return-pipe C is shown as provided with a stop-valve, C', a check-valve, C², and a valved 80 branch, C³, beyond the valves C' and C², measuring from the generator.

B' is a prolongation of the steam-pipe B for the conduct of steam to one or more engines or other steam-using devices, and said pipe 85 B' is provided with a valve, B².

As more fully set forth in one of said Irving applications for patent, the operation of this system is to force the water of condensation formed in the steam-pipe B and the water entrained into said steam-pipe from the generator upward through the pipe C and to deliver the same into the leg thereof, through which it falls ultimately into the generator. In this operation the water returned to the 90 generator through the pipe C is carried therein by the steam in the form of small detached bodies, waves, or particles suspended in the steam, and the movement of the steam through

the return-pipe is due to the difference in pressure between the steam-pipe and the low-pressure chamber in the return-pipe. It is desirable to the continued successful operation of the apparatus that the aggregate of the detached water bodies in the riser or ascending portion of the return-pipe C shall not be greater than the mass of water contained in the leg of said return-pipe which terminates in the generator. As the water column will rise in the leg of the return-pipe to a considerable distance above the water-level of the generator by reason of the unequal pressures upon opposite ends of said water column necessary to be established for the purpose of giving a desired flow of steam through the return-pipe, it has been found necessary in some cases to prolong the leg of the return-pipe an objectionable distance above the water-level of the generator. Manifestly it is desirable, at least in many situations, that said prolongation of the leg shall be as short as possible, and it is also plain that the more compact or solid the mass of water within said leg the shorter said leg may be. When the leg of the return-pipe terminates in an open end which is directed downwardly, as shown in Fig. 1, it has been found that bubbles of air or gas rise into the leg of the return-pipe and separate the water body into parts, so that a mass of water within said leg thus separated will occupy a greater vertical space, and thus require the leg to be made longer than it would otherwise need to be. It is one object of my invention to remedy this difficulty, and, as a general statement, this is done by locating the mouth of the return-pipe out of the course of the rising bubbles.

In Fig. 2 the remedy is provided by bending the lower end of the leg of the return-pipe upward, as shown at C⁴. In this construction it is contemplated that the leg shall terminate below the water-line of the generator, so that the water in the generator and that in the leg constitute in effect a single or continuous body. Another construction having the mouth of the leg in the water-space of the generator and attaining the same end is shown in Fig. 5, where a deflecting-plate, C⁵, is suspended below the open end of the leg by arms c c, leaving a space between the open end of the leg and the deflecting-plate. This deflecting-plate being of sufficient breadth relative to the size of the opening in the leg, as indicated, serves to deflect the course of the rising bubbles of air or gas to one side or the other of the mouth of the leg, and thus to prevent their entering the latter.

In Fig. 3 the leg of the return-pipe is provided with a longer upturned end reaching above the water-level and terminating in the steam-space of the generator. In this construction it will be necessary to charge the leg with its water column to prevent the escape of the contents of the boiler through said return-pipe; and to this end the upper

end of said leg is provided with a funnel, c¹, with a valve, c², below it, which may represent any means through which water may be introduced to the U preparatory to putting the apparatus into operation. When steam-pressure is generated in the boiler, the first effect will be to depress the water in the upturned end of the leg and to cause it to rise proportionately in the descending portion of said leg; but by the accretion of water in the latter from the steam-pipe the column therein will gradually descend until the upturned end of the leg is full, after which it will remain full (excepting as the opposing pressures upon the water column momentarily fluctuate) and will discharge at the mouth as fast as water is delivered into the descending part of the leg. In this construction it is manifest that the mouth of the leg is located outside the course of the bubbles which arise through the water, for the reason that such course of the bubbles terminates at the water surface.

In Fig. 4 essentially the same construction is shown as in Fig. 3, the only difference being that the U in the leg is located outside the generator. In the arrangement of this figure the check-valve C² may be desirably located in the bend at the end of the upturned part of the U.

In one of the Irving applications referred to one figure of the drawings shows the leg of the return-pipe entering the feed-pipe outside the generator and the feed-pipe entering the generator in a horizontal direction below the water surface. This construction is only partially exempt from the difficulty sought to be remedied by the above constructions, except when the feed-water is entering, in which case there is, of course, a continued flow of water from the mouth of the feed-pipe into the generator. When the feed-water is not being supplied, there is, as in all cases of the return, a fluctuation or short ebb and flow of the water in the leg constantly taking place, and on the ebb bubbles rising past the mouth of the feed-pipe are taken in and sometimes reach the leg of the return. It is of course understood that the bubbles which enter the return-pipe as arranged by Irving ultimately collapse or condense; but there is, nevertheless, such a number of such bubbles uncondensed in the water column within the return-pipe as to beget the objection herein sought to be remedied.

Next, referring to the improvement in the condensing-chamber, it should be remarked that (as fully explained in one of the Irving applications above referred to) the interior of the return-pipe C from the surface of the water in the leg thereof and extending indefinitely in said pipe is properly a condensing-chamber, and that the condensation of steam therein may be the occasion of the rush of steam from the steam-pipe through said return-pipe, by which the water is carried upward therein and into the depending leg there-

of. There is manifestly a point in this chamber toward which pressure tends from both directions, which point will depend for its precise location upon the distribution of the said

- 5 space within the return-pipe—*i. e.*, in the relative proportions of the parts of said space—and upon the location of the region of greatest heat radiation. It is also manifest that greater activity and certainty in the operation 10 of the condensing-chamber will be obtained by locating this center of equilibrium of pressure forces as near as practicable to the surface of the water in the leg of the return-pipe. To attain this result, I have provided an enlargement 15 in the return-pipe near the generator, as indicated at C⁶ of Fig. 7. Such a local enlargement of the return-pipe obviously gives a greater radiating-surface in said pipe at the point of its enlargement, and not only 20 results in bringing the focus of forces (so to speak) nearer to the place where such enlargement is located, but increases the force, dependent upon radiation or condensation. This enlargement of the condensing-chamber is 25 preferably located in the vertical part of the return-pipe; but it has been found effective in only less degree when located in the upper horizontal portion of said return-pipe near to the leg.

- 30 In Fig. 8 the enlargement C⁶ of the condensing-chamber is situated outside the vertical leg proper, but is connected therewith by a short branch pipe. Said Fig. 8 also shows the enlargement C⁶ of the condensing-chamber 35 connected by a swivel-joint, C⁷, to the return-pipe proper, by which said chamber C⁶ may be rotated out of the vertical or upright position (shown in full lines) and into the horizontal position, (shown by dotted lines,) or into a 40 position inclined either above or below the horizontal. In a horizontal position or in any inclined position said chamber C⁶ will in the use of the apparatus become filled in greater or less part with water, whereby its interior 45 steam-space will be proportionately reduced. The chamber thus constructed is therefore adjustable in the dimensions of its steam-space, and by such adjustment of its steam capacity it becomes possible to vary the force of the 50 apparatus as derived from the operation of the condensing-chamber, as may be desirable under changes in temperature.

- Fig. 9 illustrates another construction by which the steam-space of the enlargement C⁶ 55 of the condensing-chamber may be varied at pleasure. In this case the parts of the return-pipe which enter the enlargement C⁶ are screw-threaded for a considerable distance and have their ends separated. The chamber C⁶ may 60 thus be raised or lowered upon such screw-threaded parts of the return-pipe to any desired extent, bringing the end of the lower pipe to a greater or less distance from the top of the chamber. Water will fill the chamber 65 to the top of this lower pipe, and the space above the water, which is the effective steam-space of the chamber, is therefore variable,

with the same results that have been mentioned in connection with the construction of Fig. 8.

70 Other means for varying the size of the condensing-chamber may be employed, and I do not wish to be restricted to the particular devices for this purpose which I have shown; nor do I wish to be limited to the insertion 75 of a special enlargement, as C⁶, since I have found that in some situations the use of a smaller size of pipe in the ascending part of the return-pipe than in the leg, or that in the leg and upper horizontal part of the return-pipe, gives the proper distribution of the condensing-space.

75 In another application filed by me simultaneously herewith is shown a pipe connected with the steam-pipe and answering in mode 80 of operation and in its function of raising the water of entrainment and condensation from the steam-pipe, but having its delivery end outside the generator. The enlargement 85 of the condensing-chamber herein described 90 and claimed may be used in the same way and with the same result in said externally-delivering pipe as in the pipe when made to deliver into the generator, and it is the purpose to herein cover said enlargement in all 95 uses of such pipe.

I claim as my invention—

1. The combination, with a generator and a steam-pipe, of a return-pipe communicating with both the steam-pipe and the generator, 100 said return-pipe having a descending portion which contains a pressure-balancing water column, substantially as described, and terminating in the generator by an open mouth located out of the course of the rising bubbles. 105

2. The combination, with a generator and a steam-pipe, of a return-pipe leading from the steam-pipe into the generator and having therein a body of water which forms an obstacle to the escape of the contents of the generator, which body of water is contained in a bent or U-shaped part of said return-pipe.

3. The combination, with a generator and a steam-pipe, of a return-pipe leading from the steam-pipe into the steam-space of the generator and having therein a body of water which forms an obstacle to the escape of steam from the generator, which body of water is contained in a bent or U-shaped part of said return-pipe.

4. The combination, with a steam-generator and a steam-pipe leading therefrom, of an ascending pipe connected with the steam-pipe for the conduction of water upwardly therefrom by the operation of continuous condensation and continuous steam movement in said water-conducting pipe, the latter pipe being provided with an obstacle to entrance at its delivery end and having a part thereof near the obstacle of larger diameter than the ascending portion.

5. The combination, with a generator, a steam-pipe leading therefrom, and a return or water-lifting pipe connected with the steam-

pipe, of a chamber of variable dimensions forming part of the condensing-space of said water-lifting pipe.

6. In a system of pipe-connections for steam-generators, the combination, with the descending leg of the pipe C, made in two parts, having their ends separated, of an enlarged chamber movably fitted to the ends of said parts, substantially as and for the purpose set forth.

In testimony that I claim the foregoing as my invention I affix my signature in presence of two witnesses.

WALTER BURNHAM.
